UNITED STATES PATENT OFFICE.

FRANK P. BOLAND, OF PROVIDENCE, RHODE ISLAND.

SAND-BLAST MACHINE.

SPECIFICATION forming part of Letters Patent No. 760,775, dated May 24, 1904.

Application filed February 26, 1904. Serial No. 195,364. (No model.)

To all whom it may concern:

Be it known that I, FRANK P. BOLAND, a citizen of the United States of America, and a resident of Providence, in the county of Providence and State of Rhode Island, have invented certain new and useful Improvements in Sand-Blast Machines, of which the following is a specification.

My invention relates to sand-blast machines; and it consists, essentially, in the improved construction and arrangement of means for conducting and controlling the flow of the air and sand or abrading material to and from the operating-chamber, all as will be more fully hereinafter set forth and claimed.

In the accompanying sheet of drawings, Figure 1 is a front side elevation of a sand-blast machine embodying my improvement; and Fig. 2 is a partial front view, in reduced scale, showing a modification.

In the organized sand-blast machine or apparatus A (represented in the drawings) the operating-chamber *a*, inclosed within a suitable frame having glass or transparent sides, the hinged front *a*, provided with hand-holes *h*, beveled top *a*², hopper-shaped bottom *b*, and supporting-legs *l* are or may be made substantially as common or usual.

At the center and lower end of the bottom *b* is an outlet-pipe *d* and valve *d*', through which the used or spent sand flows by gravity into the larger circulating-pipe *d*², communicating with the upper part of the machine. The sand is forced along and upwardly in said pipe *d*² by air under suitable pressure flowing through pipe *c*, via valve *c*' and reduced air-discharge nozzle *c*⁵, the latter being mounted in pipe *d*² and forming an ejector or induced current in a well-known manner.

To the center or apex of the top casing member *a*² is secured a hollow fitting *e*, communicating with said air-pipe *c* by means of the branch pipe *c*² and interposed valve *c*³. The lower portion of member *e* extends downwardly into the operating-chamber *a* and forms the nozzle *e*', from which the sand is discharged by the combined action of gravity and the force of the air flowing into the nozzle via pipe *c*², &c.

The sand just referred to is conducted into

the nozzle *e*' by means of the circulating-pipe *d*², valve *d*³, and reduced pipe *d*⁵, the latter extending downwardly from said valve through the center of fitting *e* and terminating within the nozzle at a point near the discharge end, 55 as clearly shown.

In order that the pressure of air in the operating-chamber be maintained at substantially the same pressure as the atmosphere or outer air a large vent-pipe or exhaust-pipe *f* 60 is employed, the same being in direct open communication therewith through the top of the casing. An open branch pipe *d*⁴ unites the pipes *f* and *d*², thereby practically relieving the latter from any plus or back pressure at that point and permitting the sand to flow into the nozzle-pipe *d*⁵ by gravity.

By means of my improved manner of constructing and arranging the connections it will be obvious that a continuous flow of the sand or abrading material may be attained at the discharge end of the nozzle *e*', the volume and pressure of the outflowing sand being readily controlled as desired by means of the several valves or cocks.

The spent sand flowing into the lower end of pipe *d*² is taken up by the air-blast and carried past the upper bends in the pipe, after which the air-pressure is automatically relieved by escaping via the open pipe *d*⁴ into 80 exhaust-pipe *f*, the sand then flowing by gravity alone into the nozzle *e*'. Except that at times it is desirable to control the quantity of sand discharged from said nozzle the valves *d*' and *d*³ may be omitted, the force or impact 85 of the sand being practically controlled by the air-valves *c*' *c*³.

In lieu of the arrangement of the exhaust or relief piping, as shown in Fig. 1, the circulating-pipe *d*² may be provided with branch 90 pipes *d*⁴, extending downwardly into the top of the operating-chamber, as indicated in Fig. 2, the function of the pipe *f* being the same in both cases.

An important advantage possessed by my improved sand-blast machine is that no back pressure can accumulate in the sand-feeding or circulating pipes. Consequently the sand is prevented from clogging, and the outflow is more uniform.

I do not claim, broadly, as my invention a sand-blast machine capable of continuous operation in which the used sand or abrading material is carried under pressure to the top 5 of the machine and discharged from a nozzle located in the operating-chamber.

I claim as my invention and desire to secure by United States Letters Patent—

1. In a sand-blast machine provided with a 10 main operating-chamber, the combination of a sand carrying or circulating pipe d^2 communicating with the lower end of said chamber, an air-blast pipe connected with said pipe d^2 , a stationary hollow top fitting e , having an open discharge-nozzle e' extending 15 downwardly into said chamber in communication with the outlet ends of said circulating and air pipes, an inner discharge-pipe d^5 secured to or forming a continuation of said 20 pipe d^2 extending downwardly through fitting e and into the nozzle e' , and an exhaust-pipe in open communication both with the chamber and with the circulating-pipe, whereby the pressure upon the flowing sand in the latter

pipe is relieved before it escapes from the discharge-pipe d^5 , substantially as described. 25

2. In a sand-blast machine or apparatus, the combination with the operating-chamber a provided at the top with a hollow fitting e extending downwardly into the chamber, and 30 means for transferring or conducting the waste or used sand from the bottom of the chamber to the top thereof, of a valved air-blast inlet communicating with said member e , a valved connection located in the sand-conducting device having a discharge-pipe d^5 leading downwardly therefrom through fitting e , and a continuously open exhaust-duct leading 35 from said chamber and sand-conducting means, whereby the sand is adapted to drop 40 into the discharge-pipe d^5 by gravity, substantially as shown and described.

Signed at Providence, Rhode Island, this 24th day of February, 1904.

FRANK P. BOLAND.
